(57) **CLAIM**

The ornamental design for a cosmetic instrument, as shown and described.

DESCRIPTION

1. Cosmetic instrument

1.1 : Front

1.2 : Back

1.3 : Left

1.4 : Right

1.5 : Top

1.6 : Bottom

1.7 : Perspective

Fig. 1.1 is a front view of a cosmetic instrument showing our new design; Fig. 1.2 is a rear view thereof; Fig. 1.3 is a left side view thereof; Fig. 1.4 is a right side view thereof; Fig. 1.5 is a top view thereof; Fig. 1.6 is a bottom view thereof; Fig. 1.7 is a perspective view thereof.

The broken lines in the drawings depict portions of the cosmetic instrument that form no part of the claimed design.

1 Claim, 7 Drawing Sheets
